DESIGN FOR A HOLDER FOR BEER FOAM SCRAPERS

Joseph Austin, Hartsdale, N. Y., assignor to The F. & M. Schaefer Brewing Company, Brooklyn, N. Y., a corporation of New York

Application March 22, 1943, Serial No. 109,795

Term of patent 14 years

To all whom it may concern:

Be it known that I, Joseph Austin, a citizen of the United States and a resident of Hartsdale, in the county of Westchester and State of New York, have invented a new, original, and ornamental Design for a Holder for Beer Foam Scrapers, of which the following is a specification, reference being had to the accompanying drawing, forming part thereof.

Fig. 1 is a front elevational view of a holder for beer foam scrapers showing my new design;

Fig. 2 is a top plan view thereof; and

Fig. 3 is a central vertical section thereof.

The dominant features of my design are shown in solid lines on the drawing.

I claim:

The ornamental design for a holder for beer foam scrapers, substantially as shown and described.

JOSEPH AUSTIN.
